UNITED STATES PATENT OFFICE.

WILLIAM W. MACDONALD, OF SAN FRANCISCO, CALIFORNIA.

HYDRAULIC-RAM CONTROL.

1,395,001.

Specification of Letters Patent. Patented Oct. 25, 1921.

Application filed September 3, 1919. Serial No. 321,493.

To all whom it may concern:

Be it known that I, WILLIAM W. MACDONALD, a citizen of the United States, residing at the city and county of San Francisco, and State of California, have invented new and useful Improvements in Hydraulic-Ram Controls, of which the following is a specification.

This invention relates to a hydraulic ram and particularly to a means whereby a liquid under pressure may be delivered to the ram and to a valve whereby the flow of liquid is regulated.

One of the objects of the present invention is to provide a hydraulic ram control to be employed in conjunction with the steering gear of an automobile, the rudder mechanism of a ship or similar installations. Further, to provide a mechanism of the character described, which is simple and substantial in construction, responsive, sensitive and quick in action, and in which back lash or lost movement is entirely eliminated.

Another object of the invention is to provide a hydraulic ram from which movement may be transmitted to a steering mechanism and in conjunction therewith a constantly operated pump, whereby a liquid under pressure may be delivered to hydraulically move the ram in one direction or another.

Another object of the invention is to provide a controlling valve whereby the liquid supplied may be circulated through the pump or delivered under pressure to one end or another of the ram; further, a valve by which the liquid delivered to the ram may be trapped or locked so as to prevent back lash or play in the ram.

Another object of the invention is to provide means for hydraulically balancing the controlling valve to reduce wear therein to a minimum.

Further objects will hereinafter appear.

The invention consists of the parts and the construction, combination and arrangement of parts as hereinafter more fully described and claimed, having reference to the accompanying drawings, in which—

Figure 1 is a plan view of a front end of an automobile, showing the application of the invention to the steering mechanism on the automobile.

Fig. 2 is an end view of the controlling valve.

Fig. 3 is a central, vertical section through the same.

Fig. 4 is a cross section of Fig. 3, taken on line 4—4.

Fig. 5 is a section similar to Fig. 4, taken on line 5—5 of Fig. 3.

Fig. 6 is a detailed view of the over-running clutch.

Fig. 7 is a diagrammatic view of the pump, regulating valve and the ram, showing the pipe connections through which the liquid employed is circulated.

Referring to the drawings in detail, A indicates the main frame of an automobile; 2, the front wheels; 3, the shaft supporting the same; 4, the steering knuckles; 5, the tie rod connecting the same; and 6, a link which is connected at one end with a hydraulic ram generally indicated at B, and at the opposite end with the steering knuckle. The automobile is otherwise provided with a suitable form of motor C, from which power is transmitted in the usual manner by means of a propeller shaft 7 to the rear driving wheels not here shown.

Suitably supported with relation to the main frame A is a standard form of rotary pump D, through which extends a driving shaft 8, power being transmitted to rotate said shaft by means of two separate driving connections shown at 9 and 10. Both drives consist of sprocket gears and chains, as shown, one drive being transmitted to shaft 8 from the propeller shaft 7, as indicated at 9, and one drive being transmitted direct from the engine crank shaft 11 to the pump shaft 8 by means of the sprocket chain 10, the sprocket gears secured on the pump shaft 8 being each provided with an over-running ratchet clutch of the type shown in Fig. 6. The purpose of providing two independent driving connections is to insure constant operation of the rotary pump D whether the automobile is coasting down hill or being driven by engine power. For instance, if coasting down hill it is obvious that the propeller shaft 7 will rotate while the engine crank shaft will stand still. Power will therefore be transmitted through the driving connection 9 and thereby maintain the pump in operation. Again, if the car is proceeding under engine power, it is possible that

the speed of the engine crank shaft will exceed that of the propeller shaft. Power will

then be transmitted through the driving connection 10 direct to the pump shaft. In other words, means are provided for insuring a constant operation of the pump as long as the vehicle is in motion and it is also possible to insure operation of the pump when the vehicle is standing, if the engine is kept running.

The liquid employed for the operation of the ram and the steering gear connected therewith may therefore always be maintained under pressure whenever it is desired to use the vehicle.

The mechanism employed for the purpose of directing the liquid under pressure to the ram and for controlling the amount of liquid delivered is diagrammatically illustrated in Fig. 7 in which D indicates the rotary pump, B, the ram, and E, the regulating valve. The ram consists of a cylinder 12, through which extends a piston rod 13, said piston rod being supported in bearings 14, disposed at opposite ends of the cylinder and are further provided with stuffing boxes 15 to reduce leakage to a minimum.

Secured on the piston rod within the cylinder is a piston or ram 16, and formed in the cylinder are a pair of ports 17 and 18, one being disposed at each end of the cylinder. These ports alternately serve the function of supply and discharge ports and are in this instance connected with a regulating valve E by means of a pair of pipes 19 and 20. The pump D is provided with a discharge port 21 and a return port 22, the discharge port being connected with the regulating valve by means of a pipe 23 and the return port by means of a pipe 24. Connected with the pipe 24 by means of a pipe 25 is a liquid supplying tank 26 and interposed between the tank 26 and the pipe 24 is a check valve 27, the function of which will hereinafter be described.

The regulating valve consists of a casing 28 in which is formed four ports such as indicated at 29, 30, 31 and 32, the port 29 being connected with a pipe 20, the port 30 to the pipe 19, the port 31 with a pipe 23, and the port 32 with a pipe 24. Mounted interior of the casing 28 is a disk valve 33 in which is formed a pair of ports 34 and 35. Forming a closure for the casing 28 is a head plate 36, in which is formed a stuffing box 37. Extending through the stuffing box is a shaft 38 upon which the disk valve 33 is secured. Secured on the outer end of the shaft 38 is a crank arm 39 and suitably supported with relation to the main frame A is a steering wheel 40 which is provided for the purpose of transmitting a turning movement to the shaft 38 by means of a crank arm 41 and a link 42 (see Fig. 1).

For the purpose of hydraulically balancing the disk valve 33 and also for the purpose of permitting a free circulation through

the rotary pump D, I provide an annular port 43 (see Figs. 3 and 4). This port is formed in the head plate 36 and functions in the following manner: If the disk valve assumes the dotted line position shown in Fig. 7, it is obvious that oil or other liquids circulated by the pump D will discharge through pipe 23 and enter the controlling valve E through port 31. The liquid will then pass through port 34 formed in the disk valve and will thus enter the annular port 43. The oil will then pass around said port and will discharge through port 35 and port 32 and will finally return through pipe 24 and reenter the pump D through port 22.

In other words, constant circulation through the pump D may be obtained by placing the disk valve in the position shown in Fig. 7. If it is desired to deliver the liquid supplied by pump D under pressure, to the cylinder of the ram for the purpose of moving the piston in the direction of arrow α , it is only necessary to turn the disk valve until the port 34 registers with the ports 29 and 31 and port 35 registers with ports 30 and 32. Liquid discharged by the pump D will then flow through pipe 23 and enter the controlling valve by means of port 31. It will then pass through the port 34 in the disk valve and will therefore discharge through port 29 and enter the cylinder of the ram by means of pipe 20. Simultaneously, oil will discharge from the opposite end of the ram cylinder through pipe 19, as the suction side of the pump will draw the oil from said end of the ram cylinder, due to the fact that the return pipe 24 communicates with pipe 19, by means of the communicating passage formed by port 35 as this registers with ports 30 and 32.

If it is desired to deliver liquid under pressure to move the piston 16 in a direction opposite to that indicated by arrow α , it is only necessary to move the disk valve into position where port 34 will register with ports 30 and 31 and where port 35 will register with ports 29 and 32. The liquid under pressure discharging through pipe 23 will thus enter pipe 19 by way of ports 31, 34 and 30 and liquid will simultaneously be returned to the pump by the suction or return pipe 24 as port 35 registers with ports 29 and 32.

From the foregoing description it can be seen that liquid under pressure may be constantly circulated through the pump D and the controlling valve E or it may be delivered under pressure to either end of the ram cylinder. Similarly, that liquid may be removed from either end of the ram cylinder and returned to the suction side of the pump. By providing the supply tank 26, shown in Figs. 1 and 7, it is possible to automatically re-supply any liquid which might be lost by leakage. This is due to the fact that the

5 tank is connected with the suction side of the pump and by providing a check valve, as shown in 27, it should be obvious that reverse flow or backing up of the liquid into the supply tank is positively prevented.

10 The present system of operating a hydraulic ram has several advantages. First of all, I provide a means; for instance, a pump D, whereby I maintain a liquid under sufficient pressure to operate the ram whenever required. Second, a regulating valve of simple construction is provided, whereby the liquid may be circulated through the pump or whereby it may be directed to either end 15 of the ram cylinder. Third, a regulating valve, subject to comparatively little wear and leakage has been provided, as it is hydraulically balanced by means of the port formation shown at 43. Fourth, by providing a tank such as indicated at 26, it is possible to automatically re-supply any liquid which may be lost by leakage or otherwise. Fifth, by providing a controlling valve as here shown, it is possible to trap all the liquid 20 in the cylinder of the hydraulic ram so as to prevent either admission or discharge of the liquid and as the liquid is non-compressible, it is obvious that back lash or play is positively prevented. Sixth, by providing over-running clutches such as shown 25 in Fig. 6, it is possible to drive the pump when coasting down hill or it is possible to drive the pump directly from the engine, this being of importance as it is not absolutely necessary to depend upon the engine 30 at all times for maintaining the pump in operation.

While the ram, pump and controlling valve are here shown, it is employed for the 35 purpose of operating the steering mechanism of an automobile; I wish it understood that it might be equally applicable for connection with the rudder mechanism of a ship and for other purposes. Similarly, while a 40 more or less specific design and arrangement is here shown, I wish it understood that such features may be varied within the scope of the appended claims, without departing from the spirit of the present invention.

45 By referring to Fig. 7 it will be seen that I have placed a by-pass pipe 40 between the return pipe 24 and the tank 26; further, that a pressure-reducing valve 41 is mounted in said connection. The function of this valve 50 is important as it prevents building up of excess pressure in the lines. For instance, if the last operation of the ram piston 16 required an oil pressure of 800 pounds per square inch and the valve is turned to move 55 the piston in the opposite direction, then it should be obvious that oil under a pressure of 800 pounds will be delivered to the return side of the pump. If the next operation of the ram requires a pressure of 1200 60 pounds, then an increase of pressure will

take place on the discharge side until 1200 pounds is obtained and thus pressure will finally be transmitted to the return side, thus increasing the return side pressure from 800 to 1200 pounds. In actual practice 70 I find that the pressure gradually builds up but that the valve 41 will automatically maintain the pressure at any point desired so if the valve is set for a pressure of 100 pounds and oil is delivered to pipe 24 at a 75 higher pressure then sufficient oil will bypass through the valve to reduce the pressure to 100 and thereby prevent building up of excess pressures.

Having thus described my invention, what 80 I claim and desire to secure by Letters Patent is—

1. The combination with the cylinder of a hydraulic ram, of a piston reciprocally mounted in the cylinder dividing the cylinder into two chambers, a continuously operated pump adapted to maintain a body of liquid in constant circulation, a valve casing interposed between the pump and the cylinder of the hydraulic ram, a pair of ports formed in said casing, one communicating with the discharge side of the pump, and one communicating with the suction side of the pump, a second pair of ports formed in the casing, one communicating with one end of the ram cylinder and the other with the opposite end of the ram cylinder, a valve turnably mounted within the casing adapted to form communication between the discharge and the suction side of the pump to permit a continuous circulation of the liquid through the pump and the valve, said valve also adapted to be turned so as to form communication between the discharge side of the pump and either end of the cylinder and between the suction side of the pump and either end of the cylinder, means permitting the building up of pressure on the discharge side of the pump, and means interposed between the valve and the pump for automatically unloading said pressure. 90

2. The combination with the cylinder of a hydraulic ram, of a piston reciprocally mounted in the cylinder dividing the cylinder into two chambers, a continuously operated pump adapted to maintain a body of liquid in constant circulation, a valve casing interposed between the pump and the cylinder of a hydraulic ram, a pair of ports formed in said casing, one communicating with the discharge side of the pump, and one communicating with the suction side of the pump, a second pair of ports formed in the casing, one communicating with one end of the ram cylinder and the other with the opposite end of the ram cylinder, a valve turnably mounted within the casing adapted to form communication between the discharge and the suction side of the pump to 100 105 110 115 120 125 130

- permit a continuous circulation of the liquid through the pump and the valve, said valve also adapted to be turned so as to form communication between the discharge side of the pump and either end of the cylinder and between the suction side of the pump and either end of the cylinder, means permitting the building up of pressure on the discharge side of the pump, a source of liquid supply connected with the suction side of the pump and interposed between the valve and the pump, an unloading valve interposed between the suction side of the pump and the source of liquid supply, said valve automatically unloading the maximum pressure built up on the discharge side of the pump.
3. The combination with the cylinder of a hydraulic ram, of a piston reciprocally mounted in the cylinder and dividing the cylinder into two chambers, a constantly operating pump adapted to maintain a body of liquid in constant circulation, a controlling valve interposed between the cylinder of the ram and the pump adapted to normally maintain a circulation of liquid through the pump and valve, and also adapted to deliver liquid under pressure to either end of the cylinder and simultaneously adapted to return the liquid from either end of the cylinder to the pump, means permitting the building up of pressure in the liquid delivered by the pump and an unloading device interposed between the valve and the suction side of the pump adapted to be adjusted to unload the maximum pressure produced on the discharge side of the pump and also adapted to maintain a predetermined pressure on the suction and discharge side of the pump.
4. The combination with a cylinder of a hydraulic ram, of a piston reciprocally mounted in the cylinder and dividing the cylinder into two separate chambers, a source of liquid supply, means for maintaining said liquid in circulation and for producing a pressure thereon, a regulating valve adapted to deliver the liquid under pressure to either end of the cylinder and adapted to simultaneously return the liquid from either end of the cylinder, and means interposed between the valve and the suction side of the pump for maintaining a predetermined pressure on the suction and discharge side of the pump, said means also adapted to unload any excess pressure established on the discharge side of the pump.
5. In a device of the character described a continuously operating pump adapted to maintain a body of liquid in constant circulation and adapted to impart pressure thereto, a prime mover to which the liquid under pressure is adapted to be delivered for operation thereof, a controlling valve interposed between the pump and the prime mover, said valve adapted to maintain a circulation of liquid through the pump and valve, and also adapted to deliver the liquid under pressure to the prime mover and simultaneously adapted to return the liquid to the pump, a source of liquid supply connected with the suction side of the pump only and an unloading valve interposed between the valve and the suction side of the pump and adapted to discharge into the source of liquid supply to unload the pressures built up by the pump during operation of the prime mover, said unloading valve also adapted to maintain a predetermined pressure both on the suction and discharge side of the pump.
6. The combination with a continuously operating rotary pump and a ram cylinder, of a piston reciprocally mounted in the cylinder and dividing the cylinder into two separate chambers, a controlling valve interposed between the pump and the cylinder, said valve comprising a casing having a pair of ports formed therein, one adapted to communicate with a discharge side of the pump and one with the suction side of the pump, a second pair of ports formed in the casing, one communicating with one end of the cylinder and one with the opposite end of the cylinder, a disk valve within the casing, a pair of ports formed in said disk valve, a head plate for the casing inclosing the disk valve, and an annular port formed in the head plate to hydraulically balance the disk valve.
7. The combination with a continuously operating rotary pump and a ram cylinder, of a piston reciprocally mounted in the cylinder and dividing the cylinder into two separate chambers, a controlling valve interposed between the pump and the cylinder, said valve comprising a casing having a pair of ports formed therein, one adapted to communicate with a discharge side of the pump and one with the suction side of the pump, a second pair of ports formed in the casing, one communicating with one end of the cylinder and one with the opposite end of the cylinder, a disk valve within the casing, a pair of ports formed in said disk valve, a head plate for the casing inclosing the disk valve, an annular port formed in the head plate to hydraulically balance the disk valve, and means for turning the disk valve.
8. The combination with a continuously operating rotary pump and a ram cylinder, of a piston reciprocally mounted in the cylinder and dividing the cylinder into two separate chambers, a controlling valve interposed between the pump and the cylinder, said valve comprising a casing having a pair of ports formed therein, one adapted to communicate with a discharge side of the pump and one with the suction side of the pump.

5 pump, a second pair of ports formed in the casing, one communicating with one end of the cylinder and one with the opposite end of the cylinder, a disk valve within the
 10 casing, a pair of ports formed in said disk valve, a head plate for the casing inclosing the disk valve, an annular port formed in the head plate to hydraulically balance the disk valve, means for turning the disk valve, and
 15 a liquid supplying tank connected with the suction side of the pump, and a check valve interposed between the supply tank and the suction side of the pump to permit flow from the liquid supplying tank to the suction side in one direction only.

9. The combination with the cylinder of a hydraulic ram, of a piston reciprocally mounted in the cylinder dividing the cylinder into two chambers, a continuously operated pump adapted to maintain a body of liquid in constant circulation, a valve through which said liquid is adapted to be circulated, a pair of pipes connecting the valve with the suction and discharge sides 25 of the pump respectively, a second pair of pipes connected with the valve and with opposite ends of the ram cylinder, a supply tank connected with the suction pipe of the pump, a by-pass pipe connected with the 30 suction pipe and the supply tank, and a pressure reducing valve in the by-pass connection.

10. The combination with the cylinder of a hydraulic ram, of a piston reciprocally mounted in the cylinder dividing the cylinder into two chambers, a continuously operated pump adapted to maintain a body of liquid in constant circulation, a valve through which said liquid is adapted to be circulated, a pair of pipes connecting the valve with the suction and discharge sides 35 of the pump respectively, a second pair of pipes connected with the valve and with opposite ends of the ram cylinder, a supply tank connected with the suction pipe of the pump, a by-pass pipe connected with the suction pipe and the supply tank, a pressure reducing valve in the by-pass connection, and a check valve interposed between the 40 supply tank and the suction pipe.

11. The combination with the cylinder of a hydraulic ram, of a piston reciprocally mounted in the cylinder dividing the cylinder into two chambers, a continuously operated pump adapted to maintain a body of liquid in constant circulation, a valve through which said liquid is adapted to be circulated, means connecting the valve with the suction and discharge sides of the pump respectively, other means connecting the valve with the opposite ends of the ram cylinder, an automatic priming tank connected with the suction side of the pump and in constant communication therewith, and means also connected with the suction 55 side of the pump and interposed between the valve and the suction side of the pump for automatically preventing the building up of pressures beyond predetermined limits on the suction side of the pump when the valve 60 is turned to a position where it permits continuous circulation of liquid through the valve and the pump.

12. The combination with a double ended ram and a pump for delivering liquid under pressure thereto, of a valve interposed between the ram and the pump, said valve adapted to form a circulating connection between the discharge and the suction side of the pump, and also adapted to direct the 70 liquid under pressure to either end of the ram and to return the liquid to the suction of the pump from either end of the ram, an automatic priming tank interposed between the valve and the pump and in constant 75 communication with the suction side of the pump, and other automatic actuated means interposed between the valve and the pump and connected with the suction side of the pump to prevent building up of pressures on 80 the suction side beyond a predetermined pressure.

In testimony whereof I have hereunto set my hand in the presence of two subscribing witnesses.

WILLIAM W. MACDONALD.
